ORGANOMETALLIC COMPOUNDS

Thomas H. Coffield, Farmington, and Rex D. Closson, Northville, Mich., assignors to Ethyl Corporation, New York, N.Y., a corporation of Delaware
No Drawing. Filed Oct. 18, 1957, Ser. No. 690,906
4 Claims. (Cl. 260—429)

This invention relates to novel organometallic compounds and more particularly to aromatic compounds of manganese. In addition, the present invention relates to manufacture and use of the above compounds.

It is an object of this invention to provide a new class of organometallic compounds. More particularly, it is an object to provide new compounds of manganese which are relatively stable and which are soluble in organic media, particularly hydrocarbons. Another object is to provide compounds of the above type which are useful as anti-knocks in gasoline used for internal combustion engines. Still another object is to provide a novel process for manufacture of such compounds and fuel compositions containing the same. Other objects and advantages of this invention will be more apparent from the following description and appended claims.

The above and other objects of this invention are accomplished by the provision of a novel class of compounds having an aromatic molecule coordinated with a manganese atom, the compound being stabilized by additional coordination with two carbonyl groups and a cyano group, the aromatic molecule contributing six electrons, the carbonyl groups each contributing two electrons and the cyano group contributing one electron to the manganese, thereby giving the manganese a total of eleven additional electrons and resulting in the manganese atom having the configuration of krypton. More specifically, the aromatic cyano manganese dicarbonyl compounds of this invention have the general formula

wherein A is an aromatic molecule.

The compounds of this invention are unexpectedly stable to light, heat and other influences. As such, these compounds are very useful in many applications wherein stability is an important factor. The compounds are also coordination complexes and thus are soluble in organic media, particularly of the hydrocarbon type. These compounds are also antiknocks and, in use, are preferably injected into internal combustion engines as a component of the fuel mixture.

Typical examples of compounds of this invention are benzene cyanomanganese dicarbonyl, toluene cyanomanganese dicarbonyl, o-xylene cyanomanganese dicarbonyl, p-xylene cyanomanganese dicarbonyl, mesitylene cyanomanganese dicarbonyl, diphenyl cyanomanganese dicarbonyl, tetratin cyanomanganese dicarbonyl, ethylbenzene cyanomanganese dicarbonyl, n-octyl benzene cyanomanganese dicarbonyl, and the like.

The aromatic compounds coordinated to the metal in the compounds of this invention which are represented by A in the above formula are in general compounds preferably containing an isolated benzene nucleus. That is, aromatic compounds which are free of aliphatic unsaturation on a carbon atom adjacent the benzene ring and which do not contain unsaturation on a carbon atom of a fused ring which is adjacent the benzene nucleus. That is, the aromatic compounds which are preferred for this invention have no aliphatic double bond in conjugated relationship to the ring. Thus, aryl and alkyl substituted aromatic compounds are also preferred as are fused ring compounds having isolated benzene nuclei, that is, having no unsaturation on a carbon atom adjacent to a benzene ring. Aro-

2

matic compounds having from 6 to 18 carbon atoms are generally preferred in compounds of this invention. Benzene itself, mesitylene, toluene, biphenyl, tetratin, methylbiphenyl, and the like are examples of applicable aromatic compounds.

Typical examples of other compounds which are also suitable and which do not have an isolated benzene nucleus are styrene cyanomanganese dicarbonyl, methylstyrene cyanomanganese dicarbonyl, naphthalene cyanomanganese dicarbonyl, and the like.

The compounds of this invention can be prepared by a number of techniques. One typical method is to form the desired compound by decarbonylating the corresponding aromatic metal tricarbonyl cyanide by pyrolysis in accordance with the following equation

wherein A is an aromatic molecule as defined above.

20 This pyrolysis can be conducted at a temperature of between about 20° and 300° C., but is usually carried out between about 50° and 200° C. Likewise, while not essential, the reaction is best conducted in an inert liquid medium and preferably in a solvent for the tricarbonyl reactant but which is not a solvent for the product. For this reason, polar solvents are frequently preferred.

The pyrolysis to form the aromatic cyanomanganese dicarbonyl can be accomplished simultaneously with the formation of the aromatic manganese tricarbonyl cyanide reactant. For example, a typical method for producing the aromatic manganese tricarbonyl cyanide involves the reaction of an aromatic manganese tricarbonyl halide with an active cyanide compound. This reaction can be conducted at temperatures defined above for pyrolysis, 30 i.e., 20-300° C., to simultaneously produce the compounds of this invention. Likewise, the aromatic manganese tricarbonyl halide does not require isolation prior to conversion to the compounds of the present invention.

A typical series of reactions which can be conducted to 40 form the aromatic manganese tricarbonyl cyanide reactant is as follows:

wherein X is a halogen, M is a metal and m is the valence of the metal M. Thus, the above reactions can be conducted separately and, in each instance, the desired intermediate separated and isolated. Alternatively, the reactions can be conducted simultaneously or sequentially without separation of products.

The halogenation of the manganese pentacarbonyl (2) 55 can be conducted over a wide temperature range such, for example, as -70° to 100° C. although the reaction is preferably conducted at a temperature of 0° to 50° C. The reaction is preferably conducted in an inert liquid, preferably one which is a solvent for the manganese pentacarbonyl, for example, chlorinated hydrocarbons such as ethyl chloride and carbon tetrachloride, and the like; aliphatic hydrocarbons such as pentane and hexane; aromatic solvents such as benzene, toluene and xylene; solvents such as carbon disulfide and organic acids such as an acetic acid. The concentration of solvent is not critical as long as there is enough to provide solubility for manganese carbonyl.

Any of the halides are suitable in this reaction such as, for example, the chlorides, bromides, iodides or fluorides.

70 The reaction of the aromatic compound with the halogen manganese pentacarbonyl (3) is generally catalyzed by a Friedel-Crafts catalyst and is normally conducted

at a temperature of from about 20° to 300° C. A more preferred temperature range is in the order of 50° to 200° C.

By a Friedel-Crafts catalyst is meant a salt having electrophilic characteristics. These are usually halides of metals of groups IIA, IIB, IIIA, IVB, VB, VIB, VIIB and VIII of the periodic table. The preferred halides are halides of groups IIIA, IVB and VIII. Illustrative examples of preferred metal halides are boron trifluoride, boron trichloride, boron tribromide, boron triiodide, aluminum trichloride, aluminum trifluoride, titanium tetrachloride, titanium tetrabromide, ferric chloride, and the like. Also in many instances, it is desirable to employ the corresponding hydrohalide along with the metal halide, e.g. a boron trichloride-hydrogen chloride catalyst system. Other examples of suitable Friedel-Crafts catalysts of generally lesser activity are zinc, gallium, indium, thallium, beryllium, magnesium, zirconium, vanadium, chromium, manganese and cobalt halides.

The Friedel-Crafts reaction (3) is preferably carried out in a liquid medium consisting primarily of the aromatic compound which is reacted with the halogen manganese pentacarbonyl. Thus, if it is desired to make the benzene manganese tricarbonyl, the reaction is conducted in a benzene medium. The reaction can also be conducted in a halogenated benzene such as chlorobenzene or bromobenzene, in which event the chloroaromatic or bromoaromatic manganese tricarbonyl halide is formed. Other substituted aromatic compounds can be produced in like manner.

In addition to the aromatic compound, other solvents or diluents can be employed. Typical examples of such diluents are nitrobenzene; straight chain hydrocarbons such as pentane, hexane, decane, and the like. These diluents can be used in concentrations of from 0.01 to 100 parts per part of the aromatic compound.

Reaction of the aromatic manganese tricarbonyl halide with an active cyanide compound (4) is best conducted at temperatures of from -30° to 250° C. Most preferred operation employs temperatures of above 50° C. and below about 200° C. At the more elevated temperatures, the aromatic manganese tricarbonyl cyanide decomposes immediately to the desired aromatic manganese dicarbonyl cyanide. In this process, any active cyanide compound can be used but the cyanides of metals of groups I to III of the periodic table are preferred. Best results are obtained with the alkali metal compounds, such as sodium cyanide, potassium cyanide and lithium cyanide. Other typical examples of suitable metal cyanide compounds are calcium cyanide, magnesium cyanide and aluminum cyanide.

Any of a wide variety of solvents can be employed in Step 4, particularly polar solvents. Water, lower aliphatic alcohols and ethers such as acetone are preferred. The alcohols having alkyl groups containing 1 to 6 carbon atoms give excellent results. The concentration of solvent is not critical. Quantities of from about 0.1 part to about 100 parts per part of reactant can be used, although from about 1 to 10 parts are preferred.

The following are typical examples which illustrate the present invention and in which all parts are given by weight.

Example I

Mesitylene manganese tricarbonyl iodide (3.86 parts) was dissolved in 100 parts of hot water and, while boiling, 3 parts of potassium cyanide were added. Mesitylene cyanomanganese dicarbonyl, a yellow precipitate, was formed directly, carbon monoxide being evolved in about one mole equivalent quantities. The reaction mixture was cooled and filtered and 2.26 parts of mesitylene cyanomanganese dicarbonyl product was obtained. This product was recrystallized in water three times, washed with a small amount of diethyl ether and dried under reduced pressure. The melting point of the mesitylene cyano-

manganese dicarbonyl was 170-172° C. Chemical analysis of the product was as follows:

	Found	Calculated
Carbon.....	55.8	56.0
Hydrogen.....	4.79	4.65
Nitrogen.....	5.45	5.45

An infrared spectrum confirmed the structure of this product. The product obtained in this example is an effective antiknock when used in fuels for internal combustion engines.

Example II

Mesitylene manganese tricarbonyl iodide (3.86 parts) was reacted with 2 parts of potassium cyanide, but in this example the iodide compound was dissolved in 150 parts of ice-cold water. A white precipitate was formed immediately which was thereafter filtered and washed with ethyl ether. This white precipitate, mesitylene manganese tricarbonyl cyanide, (2.45 parts) was analyzed by chemical analysis and by infrared analysis. This product was thereafter refluxed under nitrogen, resulting in the evolution of carbon monoxide. Upon cooling, yellow crystals separated which were thereafter recrystallized from water. These yellow crystals were mesitylene cyanomanganese dicarbonyl having a melting point of 171-172° C. This product was also analyzed and gave characteristic infrared spectrum.

Example III

Twenty-five parts of bromomanganese pentacarbonyl, 10 parts of aluminum chloride and 108 parts of mesitylene were refluxed under nitrogen until the gas evolution had terminated. After cooling the reaction mixture, the mesitylene manganese tricarbonyl bromide was hydrolyzed with 100 parts of water. The water layer was thereafter separated and treated with excess potassium cyanide. A green precipitate was formed. Thereafter sufficient sodium hydroxide (5 percent solution) was added to the reaction product to raise the pH to 8.5, under which conditions the color of the solution changed to yellow. The product was then extracted with water and the extract was concentrated whereupon yellow crystals of mesitylene cyanomanganese dicarbonyl were obtained. This product was thereafter recrystallized from water giving 6.12 parts of mesitylene cyanomanganese dicarbonyl. The product was identified by infrared analysis.

When the above example is carried out in using other Friedel-Crafts catalyst such as boron trifluoride, boron trichloride-HCl and ferric chloride similar results are obtained.

Example IV

Example I is repeated except that benzene manganese tricarbonyl bromide is reacted with sodium cyanide in 150 parts of ethyl alcohol. The solution is refluxed until gas evolution ceases. Similar results are obtained except that the product is benzene cyanomanganese dicarbonyl.

Example V

Example I is repeated using xylene manganese tricarbonyl chloride in ethylene glycol solvent to produce xylene cyanomanganese dicarbonyl. The pyrolysis reaction is conducted at 100° C. until all of the freed carbon monoxide has been evolved.

Example VI

Tetralin manganese tricarbonyl iodide (4.4 parts) is dissolved in 120 parts of water. This solution is heated to a temperature of 50° C. and 3.2 parts of calcium cyanide is added over a period of 10 minutes. The heating is continued with stirring until there is no evidence of further gas evolution. The product reaction mass is then

cooled to room temperature and the tetralin cyanomanganese dicarbonyl purified as in Example I.

Example VII

Ethylbenzene manganese tricarbonyl cyanide is heated in dioxane to a temperature of 100° C. The solution is maintained at this temperature until the gas evolution ceased. The reaction mixture is then cooled to room temperature and the product ethylbenzene cyanomanganese dicarbonyl is recovered in accordance with the preceding examples.

Example VIII

Triethylbenzene manganese tricarbonyl chloride (8.3 parts) is dissolved in 250 parts of acetone. The solution is heated to a rolling boil and 5 parts of lithium cyanide is added to the solution. Carbon monoxide gas is evolved and the solution is maintained at reflux until no additional gas evolution is apparent. The triethylbenzene cyanomanganese dicarbonyl is recrystallized from triethanol amine and subsequently recrystallized twice in water. The crystals are washed with a small amount of dimethyl ether and dried at reduced pressure.

Example IX

Fifty parts of bromomanganese pentacarbonyl, 18 parts of aluminum bromide and 200 parts of n-octylbenzene are refluxed in an inert atmosphere until gas evolution has ceased. After cooling the reaction mixture, the product is hydrolyzed with 150 parts of water. The water layer is separated and 4 parts of sodium cyanide is added to this solution. Sufficient potassium hydroxide (10 percent solution) is added to the reaction product to raise the pH of the solution to 8.0. The product, n-octylbenzene cyanomanganese dicarbonyl, is thereafter recovered in accordance with the procedure of Example III.

The compounds of this invention can be employed with hydrocarbon fuels and lubricating oils for improving operating characteristics of spark ignition internal combustion engines. The compounds can be used in fuels and lubricating oils by themselves or together with other additive components, such as scavengers, deposit modifying agents containing phosphorus and/or boron, and also other antiknock agents, such as tetraethyl-lead, etc. When an aromatic cyanomanganese dicarbonyl compound is added to gasoline, a substantial increase in the octane value of the fuel results.

The compounds can be added directly to the hydrocarbon fuels or lubricating oils and the mixture subjected to stirring, mixing, or other means of agitation until a homogeneous fluid results. Alternatively, the compounds of our invention may be first made up into concentrated fluids containing solvents, such as kerosene, toluene, hexane, and the like, as well as other additives such as scavengers, antioxidants and other antiknock agents, e.g., tetraethyllead. The concentrated fluids can then be added to the fuels.

As the organo lead antiknock agent which is an ingredient of certain of the compositions of this invention, organolead compounds in general may be used. Preferable, however, are hydrocarbon lead compounds such as tetraphenyllead, tetratolyllead, and particularly tetraalkyl-lead compounds such as tetramethyllead, tetrapropyllead and the like. In general the amount of organolead antiknock agent is selected so that its content in the finished gasoline is equivalent to at least about 1 gram of lead per gallon.

Where halohydrocarbon compounds are employed as scavenging agents, the amounts of halogen used are given in terms of theories of halogen. A theory of halogen is defined as the amount of halogen which is necessary to react completely with the metal present in the antiknock mixture to convert it to the metal dihalide as, for example, lead dihalide and manganese dihalide. In other

words, a theory of halogen represents two atoms of halogen for every atom of lead and/or manganese present. In like manner, a theory of phosphorus is the amount of phosphorus required to convert the lead present to lead orthophosphate, $Pb_3(PO_4)_2$, that is, a theory of phosphorus based on lead represents an atom ratio of two atoms of phosphorus to three atoms of lead. When based on manganese, a theory of phosphorus likewise represents two atoms of phosphorus for every three atoms of manganese, that is, sufficient phosphorus to convert manganese to manganese orthophosphate, $Mn_2(PO_4)_2$.

When employing the compounds of this invention together with scavengers, an antiknock fluid for addition to hydrocarbon fuels is prepared comprising aromatic cyanomanganese dicarbonyl compounds together with various halogen-containing organic compounds having from 2 to about 20 carbon atoms in such relative proportions that the atom ratio of manganese-to-halogen is from about 50:1 to about 1:12. The scavenger compounds can be halohydrocarbons both aliphatic and aromatic in nature, or a combination of the two, with halogens being attached to carbons either in the aliphatic or the aromatic portions of the molecule. The scavenger compounds may also be carbon, hydrogen, and oxygen-containing compounds, such as haloalkyl ethers, halo-hydrins, halo esters, halonitro compounds, and the like. Still other examples of scavengers that may be used in conjunction with our manganese compounds either with or without hydrocarbolead compounds are illustrated in U.S. Patents 2,398,281, 2,479,900, 2,479,901, 2,479,902, and 2,479,903, and the like. Mixtures of different scavengers may also be used. These fluids can contain other components as stated hereinabove. In like manner, manganese-containing fluids are prepared containing from 0.01 to 1.5 theories of phosphorus in the form of phosphorus compounds. To make up the finished fuels, the concentrated fluids are added to the hydrocarbon fuel in the desired amounts and the homogeneous fluid obtained by mixing, agitation, etc.

The ratio of the weight of manganese to lead in fluids and fuels containing the two components can vary from about 1:880 to about 50:1. When no lead is present, the latter figure becomes 1:0. A preferred range of ratios, however, when both the manganese compounds of this invention and hydrocarbolead compounds are employed, is from about 1:63 to about 30:1.

The following examples are illustrative of fluids and fuels containing our new compounds.

50

Example X

To 1000 gallons of a commercial fuel having an initial boiling point of 90° F. and a final boiling point of 406° F. is added 55 grams of benzene cyanomanganese dicarbonyl, and the mixture subjected to agitation until the additive is distributed evenly throughout the fuel, in an amount equivalent to 0.013 gram of manganese per gallon of fuel.

55

Similar results are obtained with other aromatic cyanomanganese dicarbonyls such as xylene cyanomanganese dicarbonyl, mesitylene cyanomanganese dicarbonyl, and the like.

60

Fuels containing mixtures of two or more aromatic cyanomanganese dicarbonyls, such as the mixture of benzene cyanomanganese dicarbonyl and xylene cyanomanganese dicarbonyl are prepared in a manner similar to that employed in the above example.

65

Example XI

To 10 parts of benzene cyanomanganese dicarbonyl is added 5 parts of ethylene dichloride and the mixture agitated until a homogeneous fluid results. The manganese to chloride atom ratio in this fluid is 1:12 and represents 6 theories of halogen based on the manganese. This fluid is added to hydrocarbon fuels in amounts so as to pro-

vide improved fuels containing 0.015 gram, 0.03 gram, 6 grams and 10 grams of manganese per gallon.

Example XII

To 13.2 parts of lead in the form of tetraethyllead in an antiknock fluid containing 0.5 theory of bromine as ethylene dibromide and 1.0 theory of chlorine as ethylene dichloride, wherein the theories of halogen are based upon the amount of lead present, is added 0.015 part of manganese in the form of mesitylene cyano-manganese dicarbonyl.

This fluid is then added to a commercial hydrocarbon fuel having an initial boiling point of 82° F. and a final boiling point of 420° F. in an amount so as to provide 13.2 grams of lead and 0.015 gram of manganese per gallon.

Example XIII

To a fuel containing 0.02 gram of lead per gallon as diphenyldiethyllead, 1.0 theory of bromine as ethylene dibromide, and 0.2 theory of phosphorus in the form of tricresyl phosphate, is added mesitylene cyano-manganese dicarbonyl in an amount equivalent to 0.03 gram of manganese per gallon. This small amount of manganese in the form of the compounds of this invention provides a considerable increase in the antiknock quality of the fuel as shown upon testing in a single-cylinder engine.

Other fuels and fluids are prepared in the same manner as illustrated hereinabove which contain other deposit-modifying agents, such as boric acid, borate esters, boronic esters, etc. Likewise, lubricating oils containing from about 0.1 to about 5 weight percent manganese in the form of the aromatic cyano-manganese dicarbonyl compounds of this invention are prepared, and these lubricating oils, when used in reciprocating engines, are found to have a beneficial effect on engine cleanliness and in the reduction of combustion chamber deposits.

The fuels to which the antiknock compositions of this invention are added may have a wide variation of compositions. These fuels generally are petroleum hydrocarbons and are usually blends of two or more components. These fuels can contain all types of hydrocarbons, including paraffins, both straight and branched chain; olefins; cycloaliphatics containing paraffin or olefin side chains; and aromatics containing aliphatic side chains. The fuel type depends on the base stock from which it is obtained and on the method of refining. For example, it can be a straight run or processed hydrocarbons, including thermally cracked, catalytically cracked, reformed fractions, etc. When used for spark-fired engines, the boiling range of the components of gasoline can vary from zero to about 430° F., although the boiling range of the fuel blend is often found to be between an initial boiling point of from about 80° F. to 100° F. and a final boiling point of about 430° F. While the above is true for ordinary gasoline, the boiling range is a little more restricted in the case of aviation gasoline. Specifications for the latter often call for a boiling range of from about 82° F. to about 338° F., with certain fractions of the fuel boiling away at particular intermediate temperatures.

The amount of manganese that can be employed in the form of aromatic cyano-manganese dicarbonyl compounds of this invention in hydrocarbon fuels of the gasoline boiling range can vary from about 0.015 to about 10 grams of manganese per gallon, preferably 0.03 to 6 grams of manganese per gallon. In addition, the fuel can also contain organolead antiknock agents such as tetraethyllead in amount equivalent to from about 0.02 to about 13.2 grams of lead per gallon.

The aromatic cyano-manganese dicarbonyl compounds of this invention may be incorporated in paints, varnish, printing inks, synthetic resins of the drying oil type, oil enamels and the like, to impart excellent drying characteristics to such compositions. Generally speaking,

from 0.01 to 0.05 percent of manganese as a compound of this invention is beneficially employed as a dryer in such a composition.

For example, to a typical varnish composition containing 100 parts ester gum, 173 parts of tung oil, 23 parts of linseed oil and 275 parts of white petroleum naphtha is added 3.0 parts of mesitylene cyano-manganese dicarbonyl. The resulting varnish composition is found to have excellent drying characteristics. Equally good results are obtained when other drying oil compositions and other aromatic cyano-manganese dicarbonyl compounds of this invention are employed.

Other important uses of the aromatic cyano-manganese dicarbonyl compounds of the present invention include 15 the use thereof as chemical intermediates, particularly in the preparation of metal and metalloid containing polymeric materials. In addition, some of the aromatic derivatives of this invention can be used in the manufacture 20 of medicinals and other therapeutic materials, as well as agricultural chemicals such as, for example, fungicides, defoliants, growth regulants, and so on.

Having fully described the novel compounds of the present invention, the need therefor, and the best methods 25 devised for their preparation, we do not intend that our invention be limited except within the spirit and scope of the appended claims.

We claim:

1. A compound having an aromatic hydrocarbon molecule coordinated with manganese, the compound being 30 stabilized by additional coordination with two carbonyl groups and a cyano group, the aromatic hydrocarbon molecule contributing six electrons, the carbonyl groups each contributing two electrons and the cyano group contributing one electron to the manganese, thereby giving 35 the manganese a total of eleven additional electrons and resulting in the manganese atom having the electron configuration of krypton.

2. The process for producing compounds having an aromatic hydrocarbon molecule coordinated with manganese, the compound being stabilized by additional coordination with two carbonyl groups and a cyano group, the aromatic hydrocarbon molecule contributing six electrons, the carbonyl groups each contributing two electrons and the cyano group contributing one electron to the manganese, thereby giving the manganese a total of eleven additional electrons and resulting in the manganese atom having the electron configuration of krypton, comprising 40 decarbonylating an aromatic hydrocarbon manganese tricarbonyl cyanide by heating to a temperature of 20-50 300° C.

3. Mesitylene cyano-manganese dicarbonyl.

4. The process of claim 2 wherein:

(1) the compound produced is mesitylene cyano-manganese dicarbonyl; and 55 (2) The aromatic hydrocarbon manganese tricarbonyl cyanide reactant is mesitylene manganese tricarbonyl cyanide.
